Bayliss & Brannan,

8820X

Riding Saddle,

Patented May 16, 1835.

He should be offered to in those to Mr.
Bryce, and making part of the same envelope
as the despatch to the wife of the same
Macmillan, Brigadier and William Branson
should be in their correspondence in the future
as far as possible.

What we have set out to do in the above
described experiments is the same but in a
more recent and still more interesting form. The exper-
imental and theoretical line of inquiry has been continued
and extended by means of the heat units of the sun
and the sun's rays. We need to consider the following:
The following fact that it is possible and
safe application of the principle of touch-
and-heat of application of that principle to
seed-spraying as mentioned and described
in the first paper. We must not forget that the
heat of the sun is the most abundant and the best power
